(57) **CLAIM**

The ornamental design for a sock toe, as shown and described.

DESCRIPTION

FIG. 1 is a top plan view of a sock toe showing my new design; FIG. 2 is a left side view of the sock toe; FIG. 3 is a right side view of the sock toe; and, FIG. 4 is a bottom plan view of the sock toe.

The broken lines show environmental structure and form no part of the claimed invention.
